UNITED STATES PATENT OFFICE.

JOHN F. O'CONNOR, OF CHICAGO, ILLINOIS, ASSIGNOR, BY MESNE ASSIGNMENTS, TO
W. H. MINER, INC., A CORPORATION OF DELAWARE.

SHOCK-ABSORBING MECHANISM.

Application filed October 1, 1924, Serial No. 740,934. Renewed November 28, 1927.

This invention relates to improvements in shock absorbing mechanisms.

One object of the invention is to provide a shock absorbing mechanism of high capacity adapted for railway draft riggings, having initial, relatively light resistance and relatively higher capacity during the remainder of the compression stroke.

Another object of the invention is to provide a shock absorbing mechanism of the character indicated, of the double ended type, including relatively movable main followers, a friction shell and a plurality of groups of friction shoes coacting with the shell, wherein the shoes are forced against the friction surfaces of the shell by front and rear wedge means resisted by springs interposed respectively between the latter and the front and rear main followers.

Other objects and advantages of the invention will more clearly and fully appear from the description and claims hereinafter following.

In the drawings, forming a part of this specification, Figure 1 is a longitudinal, horizontal, sectional view of a railway draft rigging, showing my improvements in connection therewith. Figures 2 and 3 are transverse, vertical, sectional views of the shock absorbing mechanism proper, corresponding respectively to the lines 2-2 and 3-3 of Figure 1. And Figure 4 is a longitudinal, vertical, sectional view, partly broken away, corresponding substantially to the line 4-4 of Figure 1, with the springs omitted.

In said drawings, 10-10 indicate channel-shaped center or draft sills of a railway car underframe to the inner faces of which are secured front stop lugs 11 and rear stop lugs 12. The inner portion of the drawbar is designated by 13, to which is secured a hooded yoke 14. Disposed within the yoke is the shock absorbing mechanism proper, including front and rear follower acting members. The movable parts of the draft rigging are supported in operative position by a detachable saddle plate 15.

The improved shock absorbing mechanism proper, as shown, comprises broadly, front and rear follower casings A-A; a central friction shell B; front and rear wedges

C-C; two groups of friction wedge shoes D-D; tandem arranged twin spring resistance elements E-E; and a pair of retainer bolts F-F.

The front and rear follower casings A are of like construction, each being of hollow boxlike form and open at its inner end. Each follower casing comprises spaced, longitudinally disposed top and bottom walls 16-16, spaced, longitudinally disposed side walls 17-17, and a vertically disposed, transverse end wall 18. The end wall 18 has a pair of inwardly projecting hollow bosses 19-19 disposed midway between the top and bottom of each casing and equally spaced on opposite sides of the longitudinal axis of the mechanism. The side walls of each casing A are cut out centrally as indicated at 20 to accommodate the outer sides of the outermost coils of the spring resistance elements E.

The friction shell B, which is also of rectangular box-like form, is open at its opposite ends and has spaced, longitudinally disposed, horizontal top and bottom walls 21-21 and spaced, longitudinally disposed side walls 22-22. Midway between the ends of the shell B, the side walls are inwardly offset as shown at 23. The top and bottom walls 21 of the shell are provided with opposed groups of friction surfaces, each group being composed of two sets, the surfaces of one set being designated by 24 and those of the other set by 25. The friction surfaces of each group are preferably eight in number, there being four surfaces 24 and four surfaces 25. The opposed surfaces 24 converge slightly rearwardly of the mechanism, while the opposed surfaces 25 converge forwardly thereof.

The front and rear wedge members C are of like construction, each being in the form of a block having a pair of inwardly converging wedge faces 26-26 at the inner side thereof, the wedge faces 26 being adapted to respectively cooperate with the two groups of friction wedge shoes D. Each wedge member C has laterally extending flanges 27-27 on the opposite sides thereof, thereby providing a relatively wide, outer bearing surface adapted to coact with the corresponding set of twin springs E. It will be

noted that each wedge member C coacts with the corresponding twin springs in the manner of a spring follower, the main body portion of each wedge member C working between the inwardly offset wall portions 23 of the shell B.

The friction wedge shoes D comprise two groups disposed on opposite sides of the longitudinal axis of the mechanism, and as herein illustrated are preferably disposed at the top and bottom sides of the shell respectively. The friction shoes composing each group are of like construction, each being in the form of a relatively heavy plate cut away at the inner and outer ends to provide wedge faces 126 correspondingly inclined to and adapted to cooperate with the corresponding wedge faces 26 at the same side of the front and rear wedge members. Each shoe D has an extension 127 at one end thereof, which is in the form of an elongated arm or finger and is adapted to coact with the corresponding main follower member A. The friction wedge shoes of each group are preferably eight in number, four of the shoes of each group cooperating with the corresponding friction surfaces 24 of the shell B, each shoe having an elongated friction surface 124, cooperating with one of the faces 24. The remaining four shoes of each group cooperate with the corresponding friction surfaces 25, each being provided with elongated friction surfaces 125 for that purpose. The shoes cooperating with the respective friction surfaces 24 and 25 are reversely arranged, that is, the former have their arms 127 forwardly disposed and the latter having their arms 127 rearwardly disposed. The parts are so proportioned that when the mechanism is in normal, full release position, the inner ends of the front and rear follower casings are slightly spaced from the front and rear ends of the respective arms 127, as clearly indicated in Figures 1 and 4. In this connection, it is pointed out that the shell B is adapted to telescopically receive the inner ends of the front and rear follower casings. Shoulders 28 are provided on the top, bottom and side walls of each casing A which are normally spaced from the corresponding outer end of the friction shell B and adapted to engage the latter when the mechanism is fully compressed to limit the relative movement of the front and rear follower members and casing A. When the mechanism is fully compressed, the casing A together with the front and rear follower members act as a solid stop column to directly transmit the load to the corresponding stop lugs of the draft sills.

The tandem spring resistance elements E—E consist of twin arranged front and rear spring units, each unit including an inner, relatively light coil bearing at its

outer end on the corresponding boss 19 of one of the follower casings A and bearing on its inner end on the corresponding wedge member E. The inner coil is surrounded by an outer, relatively heavier coil having 70 its opposite ends bearing directly on the wall 18 of the corresponding casing and the outer surface of the corresponding wedge member C.

The retainer bolts are disposed at opposite sides of the longitudinal axis of the mechanism and each bolt has its opposite ends anchored in the corresponding hollow boss 19 of the front and rear follower casings A. The shank of each bolt extends 80 through the inner coils of the front and rear spring resistance elements and aligned openings in the spring follower acting wedge members C. The retainer bolts F serve to maintain the mechanism of uniform, overall 85 length and also hold the parts assembled under initial compression.

When the parts are in full release position, the expansive action of the front and rear spring resistance elements maintains 90 all of the parts properly centered, the wedge faces 26 of the front and rear wedge members coacting with the front and rear wedge faces of the two groups of shoes to properly center the latter. The groups of shoes are 95 held assembled between the offset portions 23 of the side walls 22 of the shell A, and guided therebetween for relative sliding movement, and for movement with reference to the friction surfaces of the shell. In this 100 connection, it will be noted that alternate shoes D of the two groups cooperate with the front follower to be moved rearwardly thereby, and the remaining shoes of the two groups cooperate with the rear follower to 105 be moved forwardly thereby, forming separate and independent spring and friction units, giving the whole device a combined capacity double that of a single set.

As wear occurs on the various friction and wedge faces, compensation therefor is had due to the expansive action of the front and rear sets of twin springs which as hereinbefore pointed out are under initial compression, suitable clearance for this purpose 110 being left between the inner ends of the spring follower acting wedge members C.

The operation of the mechanism, assuming an inward or buffing movement of the drawbar, is as follows: As the drawbar moves 115 rearwardly the front follower casing A is forced rearwardly also, compressing the front pair of twin spring resistance elements E and through the front wedge member C, the two groups of friction shoes D and the rear wedge member C, in turn compressing the rear spring resistance elements E. The two wedges C and the two groups of shoes D will with the shell B, thus be forced rearwardly substantially as a unit, and due to 120 125 130

the friction between the shoes D and the friction shell B the latter will be forced rearwardly in unison with the shoes. During this action, the front and rear sets of 5 twin springs will be substantially equally compressed and function in the manner of a tandem set of twin springs. This action will continue until the inner ends of the top and bottom walls of the front follower 10 casing A engage the projecting arms 127 of the wedge friction shoes D cooperating with the friction surface 24 of the shell A, and the front ends of the top and bottom walls of the rear follower casing A are engaged by the ends of the arms 127 of the 15 friction shoes D which cooperate with the friction surfaces 25 of the shell, whereupon the shoes D will be moved relatively to each other in unison with the front and rear follower casings, setting up a pronounced wedging 20 action and also effecting relative movement of the two sets of friction wedge shoes coacting with the respective friction surfaces 24 and 25 and the front and rear 25 wedges. The wedges C will be thus moved apart, further compressing the front and rear spring resistance elements E. Due to the converging relation of the opposed sets of friction surfaces 24 and 25, a differential 30 action will be had, thereby effecting an increased rate of movement of the wedge members, still further compressing the main spring resistance elements.

As will be evident, the resistance during 35 the last described portion of the compression stroke is greatly increased over that had during the initial action of the mechanism inasmuch as each set of twin springs is compressed from both ends, each set having an 40 amount of compression equal to nearly full action of the device, and to the resistance thus offered is added the frictional resistance between the various shoes D and the friction surfaces of the shell. Relative movement 45 of the front and rear follower casings and the shell A will be limited by engagement of the shoulders of the former with the outer ends of the latter as hereinbefore pointed out.

During draft the action of the mechanism 50 is substantially the same as that hereinbefore described, the only difference being that the movement is reversed, the rear casing A being moved toward the front follower casing which is held stationary.

Upon reduction of the actuating force, the 55 springs E act to immediately force the casings A apart. As the casings are moved out of engagement with the corresponding wedge friction shoes D, the wedging pressure is reduced, thereby permitting the springs to restore all of the parts to normal position. It will be evident that the restoration of the front and rear casings is effected independently of any releasing action of the friction

wedge system and that therefore in case the friction wedge system should become stuck and not release properly, the spring elements would still be available to absorb the next succeeding shock to which the mechanism 70 is subjected.

I have herein shown and described what I now consider the preferred manner of carrying out my invention, but the same is merely illustrative, and I contemplate all changes 75 and modifications that come within the scope of the claims appended hereto.

I claim:

1. In a friction shock absorbing mechanism, the combination with front and rear 80 follower acting elements, relatively movable toward and away from each other; of tandem arranged springs interposed between said follower elements; a friction shell interposed between said follower elements, said shell having opposed, interior friction surfaces; a plurality of friction shoes cooperating with said friction surfaces, said shoes being arranged in groups on opposite sides of the axis of the mechanism, certain of the 85 shoes of each group being adapted to be actuated by one of said follower elements and the remaining shoes of said groups being adapted to be actuated by the other follower element; and front and rear wedges cooperating with said shoes, said wedges being interposed between said tandem springs.

2. In a friction shock absorbing mechanism, the combination with front and rear 100 follower acting members, relatively movable toward and away from each other; of a longitudinally disposed friction member having a plurality of opposed friction surfaces, said surfaces being disposed in groups at opposite sides of the mechanism; spring resistance elements interposed between said follower members, one of said elements being associated with each follower member; a plurality of friction elements cooperating with each follower member, each friction element 105 engaging one of said friction surfaces; and spreading means interposed between said springs and coacting with said friction elements.

3. In a friction shock absorbing mechanism, the combination with front and rear 115 follower acting members, relatively movable toward and away from each other; of tandem arranged spring resistance elements interposed between said follower members; a plurality of opposed, relatively movable friction shoes interposed between said follower members and adapted to be actuated thereby; a friction shell interposed between 120 said follower members, said shell having a plurality of friction surfaces at one side of the longitudinal axis of the mechanism cooperating with certain of said shoes, and a plurality of friction surfaces on the opposite side of said axis cooperating with the re- 125 130

maining shoes; and wedge means interposed between said tandem springs and cooperating with said friction shoes.

4. In a friction shock absorbing mechanism, the combination with front and rear follower acting members, relatively movable toward and away from each other; of tandem arranged springs interposed between said follower members; a friction shell interposed between said follower members, said shell having interior friction surfaces; and means interposed between said springs actuated by the relative movement of said follower members for forcing said springs apart, said means including a plurality or intercalated friction shoe elements having friction surfaces cooperating with the shell friction surfaces, said shoes being adapted to be moved relatively to each other by said follower members, and a pair of wedges cooperating with said shoes, each wedge member engaging one of said springs.

5. In a friction shock absorbing mechanism, the combination with front and rear followers, relatively movable toward and away from each other; of spring resistance elements interposed between said followers, one of said spring elements being associated with each follower; a plurality of wedge friction shoes coacting with each follower, the shoes coacting with one follower being alternated with the shoes coacting with the other follower; wedge pressure transmitting members coacting with each set of alternate shoes, each of said wedge pressure transmitting members coacting with one of said springs; and a rectangular friction shell having two sets of opposed friction surfaces on two walls thereof cooperating with said shoes.

6. In a friction shock absorbing mechanism, the combination with front and rear followers; of a friction shell interposed between said followers, said shell having two groups of longitudinally disposed, opposed, interior friction surfaces, said groups comprising two sets of opposed friction surfaces, the opposed surfaces of one of said sets converging forwardly of the mechanism and the opposed surfaces of the other set converging rearwardly of said mechanism, adjacent surfaces of each group being reversely inclined and alternate surfaces of each group being similarly inclined; friction means interposed between said followers, said means including wedge members and a set of friction shoes coacting with each set of opposed friction surfaces, each set of shoes being actuated by one of said followers and cooperating with one of said wedge members; and yielding, movement-resisting means interposed between each wedge member and corresponding follower acting member.

7. In a friction shock absorbing mecha-

nism, the combination with front and rear followers; of a rectangular friction shell interposed between said followers, said shell having two sets of opposed, longitudinally arranged, interior friction surfaces, the opposed friction surfaces of one set converging rearwardly of the mechanism and the opposed surfaces of the other set converging forwardly of said mechanism and the surfaces of one set being alternated with the surfaces of the other set; a group of wedge friction shoes cooperating with one of said sets of friction surfaces of the shell and adapted to be actuated by the front follower; a second group of wedge friction shoes cooperating with the remaining set of friction surfaces of the shell and adapted to be actuated by the rear follower; a wedge member cooperating with each group of shoes; and front and rear spring resistance elements cooperating with said wedge members.

8. In a friction shock absorbing mechanism, the combination with front and rear follower acting casing members; a rectangular shell interposed between said members and telescopically receiving a portion of each of the latter, said shell having a plurality of opposed, interior friction surfaces at the top and bottom thereof; tandem arranged springs interposed between said follower acting casing members, one of said springs being associated with each follower acting casing member; a pressure transmitting means engaged by each follower acting casing member and cooperating with the spring associated with the other follower acting casing member, each pressure transmitting means comprising a plurality of friction wedge shoes cooperating with certain of said top and bottom shell friction surfaces and a wedge engaging said shoes and cooperating with said last named spring.

9. In a friction shock absorbing mechanism, the combination with front and rear follower acting means; of a friction shell interposed between said follower acting means, said shell having two opposed series of longitudinally disposed, interior friction surfaces, alternate surfaces of each series diverging rearwardly with reference to the longitudinal axis of the mechanism and the remaining surface of each series diverging forwardly with reference to said axis; two sets of friction shoes cooperating with the shell friction surfaces, alternate shoes of said sets cooperating with alternate friction faces of said two series and adapted to be moved by one of said follower acting means, the remaining shoes of said sets being actuated by the other follower acting means and cooperating with the remaining friction surfaces of the shell; spreading means cooperating with alternate shoes; a second spreading means cooperating with the remaining

shoes; and a spring resistance element interposed between each follower acting means and the corresponding spreading means.

10. In a friction shock absorbing mechanism, the combination with front and rear follower acting means; of a rectangular friction shell interposed between said follower acting means, said shell having a plurality of longitudinally disposed, interior friction surfaces; tandem arranged twin springs interposed between said follower acting means; a spring follower cooperating with each of said twin springs, each of said spring followers having wedge faces; two 15 series of friction wedge shoes cooperating

with the shell friction surfaces, alternate shoes of said two series cooperating with the wedge faces of one of said spring followers and the remaining shoes of said two series cooperating with the other spring follower; means for transmitting the actuating force from one of said main follower acting means to said alternate shoes; and means for transmitting the actuating force from the other follower acting means to the remaining 25 shoes.

In witness that I claim the foregoing I have hereunto subscribed my name this 27th day of September, 1924.

JOHN F. O'CONNOR.
